UNITED STATES PATENT OFFICE

2,483,408

RELAY CIRCUIT

Nathan Garber, Brooklyn, N. Y., assignor to Federal Telephone and Radio Corporation, New York, N. Y., a corporation of Delaware

Application March 26, 1945, Serial No. 584,947

3 Claims. (Cl. 175—320)

1

This invention relates to relay circuits and more particularly to an arrangement of multiple relays wherein the operation of a slave relay is controlled by the operation of another or master relay.

In some control applications, as for instance such as disclosed in the copending applications of L. Dubin 5, Ser. No. 584,957, filed March 26, 1945, and D. D. Grieg-A. Frum-L. Dubin, Ser. No. 584,862, filed March 26, 1945, now Patent No. 2,444,439, issued July 6, 1948, which describe aspects of a radio beacon system, it becomes desirous to operate a given circuit momentarily while operating another circuit over a given period. This is the case in the above-mentioned applications when, upon the appearance of a beam signal at the beacon receiver, certain integrating condensers or other circuits are to be cleared of any previous charge prior to receiving the charge due to the new signal, while a circuit from the plate voltage supply to the detector circuits, which renew the charge on the condensers, is maintained closed for the duration of the beam signal.

It is accordingly an object of this invention to provide a multiple control circuit which makes it possible to operate one circuit temporarily upon the operation of another circuit under certain conditions over a given period.

It is a further object to provide a multiple relay circuit wherein a master relay controlling one circuit, causes a slave relay to operate momentarily with respect to another circuit.

It is still another object to provide a relay circuit which causes the momentary operation of a relay upon application of relatively continuous energy.

In accordance with a feature of the invention, a control circuit is arranged such, that when energy is applied thereto, a master relay is made to close its contacts which control the energizing circuit for a second or slave relay. Upon closure of this energizing circuit, a transient surge is caused to pass thru the slave relay. The slave relay has a return circuit to ground which provides a time constant and which is of such a character as to permit the temporary operation only of the second relay on the occurrence of a positive surge upon closing of the first or master relay.

These and other features and objects of the invention will be better understood in connection with the detailed description of the drawings, in which:

2

Fig. 1 is a circuit shown in diagrammatic form incorporating my invention;

Fig. 2 is a simplified form of a portion of the circuit of Fig. 1; and

Fig. 3 is a graphic representation of some of the operating characteristics of the circuits of Figs. 1 and 2.

Referring to Fig. 1 the circuit shown therein comprises an amplifier 1 which is adapted to receive a signal from a source which is not shown. The amplified signal, preferably in the form of a D. C. pulse, is applied to a master relay 2, the circuit being completed thru a voltage source 3 to ground at 4. The voltage source 3 also serves as a plate voltage supply B+ for the amplifier 1 thru the windings of the relay 2. The relay 2 may control, by way of the contact 5, energy from the voltage source 3 through any circuit which is to be energized as indicated at 6, and also a circuit from the source 3 to a second or slave relay 7. The relay 7 is provided with a return circuit to ground at 8 which includes a resistor 9 and a condenser 10 connected in parallel and adapted to introduce a time factor into the relay circuit as will appear hereinbelow. The slave relay 7, by way of a contact 11 may control a circuit of its own such as a by-pass to ground at 8 of a condenser 12, normally being charged with respect to the ground 8 from a charging source (not shown) over a conductor 13. The condenser 12 or other circuit controlled by contact 11 may be separate from circuit 6 or it may in some way be associated therewith as indicated.

In order to be able to render more simple the discussion of the operation of the slave relay, its circuit, including the relay 7, the resistor 9, the capacitor 10, the source of voltage 3 and the control 5 have been illustrated in Fig. 2 as a separate equivalent circuit. In this equivalent circuit the relay 7 has been shown to be comprised of an inductance L and a resistance R₁ the resistor 9 and the capacitor 10 having been referred to as R and C, respectively.

As the voltage from source 3 is applied to the relay circuit of Fig. 2 by the closing of the switch 5, a transient current surge is provided in the relay L—R as at i_T in Fig. 3. The current at first builds up rather rapidly, as determined by the values of L and C, until it reaches a point at 14 when the relay 7 closes. As the voltage across C continues to build up, the rate of build up being determined by R and R₁, and as the voltage across L continues to decline, a maximum current flow thru the relay is reached as indicated at 15. The current thereafter begins to decrease because of

the overbalance of the voltage of C over the voltage drop across the relay. After reaching a peak at 15, the current begins to decline exponentially to reach a point substantially at 16 when it becomes too small to hold the relay any longer and the relay opens. The relay current continues to decline due to a continuous build up of the voltage across C to approach asymptotically a steady state value i_0 , which is a function of the circuit resistance and may be expressed by

$$\frac{E}{R_1 + R}$$

The time interval t_c between points 14 and 16, i. e., between closing and opening, is determined by the constants of R and C, which are chosen to effect a given suitable operating period for the relay.

Upon removal of the energy operating the master relay, its contact will break and another transient will be produced in the slave relay. This transient, however, is of insufficient amplitude and/or duration to operate the relay 7. Upon again applying a control voltage to operate the relay 2, the cycle recited above will then be repeated.

In choosing the values of R and C, care should be taken that their values are such that together with L and R_1 they do not form an oscillatory circuit. Consideration is also to be given to the choice of R so that the steady state relay current i_0 is held to a value which is below the point 16 when the relay opens.

It is to be noted that the curves in Fig. 3 are approximate in the respect that no consideration has been given to the change in L due to closing of the relay, i. e., due to a change in the position of the relay armature. However, the principles of operation as outlined, are not affected thereby.

It is to be understood, of course, that the specific description of the particular embodiment is given above merely by way of illustration and is not to be considered as a limitation of my invention as set forth in the objects thereof and in the appended claims.

I claim:

1. A control system comprising a master relay having a cooperating contact, a slave relay, a source of potential for energizing said slave relay, a timing circuit including a resistor and a con- 50

denser connected in parallel, said contact, said slave relay, said source and said circuit all serially connected, a source of direct current pulses for momentarily energizing said master relay for prescribed periods of time, said contact controlling the operation of said slave relay and said circuit controlling the reduction of effective current through said slave relay to deenergize said slave relay after a period of time shorter than each of said prescribed periods of time.

5 2. A system in accordance with claim 1, wherein said slave relay comprises an inductive reactance and said timing circuit comprises the said parallel circuit, resistor and condenser in series 15 with said slave relay, values of said resistor and condenser being of such values as to render the series combination non-resonant.

20 3. A system in accordance with claim 1, wherein said slave relay has a resistance component and is designed to open when the current therein is below a given value, and the timing circuit resistor has a resistance, which in combination with said slave relay resistance provides a current through said slave relay approaching a steady 25 state value at a value less than said given value.
